UNITED STATES PATENT OFFICE.

JONATHAN FLEMING, OF MADISON, ALLEN COUNTY, INDIANA.

ROAD-SCRAPER.

SPECIFICATION forming part of Letters Patent No. 279,368, dated June 12, 1883.

Application filed April 6, 1883. (No model.)

To all whom it may concern:

Be it known that I, JONATHAN FLEMING, a citizen of the United States, residing in Madison township, in the county of Allen and State of Indiana, have invented certain new and useful Improvements in Road-Scrapers, of which the following is a specification, reference being had therein to the accompanying drawings.

10 This invention relates to that class known as "wheeled graders and smoothers," and has for its object the grading and smoothing of roads or irregular land, as will be hereinafter more particularly described.

15 In the accompanying drawings, making part of this specification, Figure 1 represents a plan view. Fig. 2 represents a vertical longitudinal section; and Figs. 3 and 4 detached portions, Fig. 3 being a section in line $\alpha\alpha$, showing the position of the king-bolt with reference to the bolster, the axle, the reach or center piece of the hounds, and the scraper, while Fig. 4 shows one of the levers for raising and lowering the scraper. Fig. 5 is a side view of 25 the end of the pole.

In the figures, A represents an axle, which is mounted upon the two wheels B B.

C C represent the hounds of the machine, and D the center bar or reach between the two, 30 the three parts being firmly secured to the axle A, the hounds being braced firmly from the axle, both behind and before, by the braces l l.

Immediately over the hounds is the bolster E. Upon this bolster, near its ends, are secured two angular blocks, E' E', which are made thicker at their inner than at their outer ends. Pivoted to these blocks, near their outer ends, are two levers, F F, one to each block, in such manner that their ends may have a partially rotary motion.

40 Secured to each block is a ratchet-segment, m. Beneath the levers F, and between small ears connected to same, are pivoted the L-shaped levers L.

45 A rod, M, connected to the short arm of the lever L, connects with a bolt, N, which plays with a coiled wire spring around it through two keepers on the under side of the lever F. The free end of the bolt is adapted 50 to catch into the teeth of the ratchet-segment, and thus station the lever F at any desired

point. The outer ends of the levers F have segments a' formed upon them, and said segments have in their faces a curved groove.

A chain, a, passes through the lever F, near the segment a', and its free end is caught, when desired, in the slot of a plate, o, secured to said lever. This chain passes around a pulley, J, on the end of the bolster, and then has its end secured to the scraper. There being 55 a chain secured to each of the levers F and to each end of the scraper, it is evident that the ends of said scraper can be alternately raised or lowered, or made to work with both ends at an equal elevation or depression.

65 The scraper proper is composed of three parts—the back board, P, which is made of wood, the bed-plate q, which is made of metal, and the knife R, which is also made of metal. The bed-plate may be in one piece, but is preferably in sections, which are firmly bolted to the back board, P. The lower end of the bed-plate is provided with two shoulders, one in front and the other at rear. The lower end of the back board rests upon the rear shoulder, 70 and the upper edge of the knife rests against the front shoulder, as seen. The bed-plate is slightly curved forward at its lower end for the purpose of forming a proper seat and rest for the knife, giving a suitable curve for carrying up the earth to the bed-plate.

75 G represents the tongue of the machine, which is connected to the forward end of the hounds by means of a brace, H. This brace has at its lower end a foot, K, which is perforated with holes to allow of different adjustments, as will be described.

80 S and T represent two metallic straps, which are connected one to the top and the other to the bottom side of the rear end of the pole. 85 These straps pass under a yoke, v, which has its ends secured to the back board of the scraper. The main strap T passes back, and has two rectangular bends in it at its end, space sufficient being left between the bends 90 to allow it to embrace the semicircle I. This strap is braced and securely connected to the back board by means of a brace, u.

I represents a semicircular brace, which is firmly secured at its ends to the back board of 95 the scraper near its ends. This brace I is provided with a series of holes, and a pin, w, passes

through the bent end *x* of the strap *T*, and also through the semicircle *I*, for the purpose of securing the two parts together. By removing the pin *w* the bent end of strap *T* may be 5 shifted upon the semicircle for giving direction to the draft of the machine through the pole.

u' represents a brace, which passes from near the bottom of the back board to the strap 10 *T*, near its rear end, being securely bolted to the strap and suitably hinged to the back board, which enables the rear end of the strap to move on the semicircle *I*, while at the same 15 time the scraper is suitably braced all the while. The brace *u* is also hinged, as seen, to the back board of the scraper.

Y represents the king-bolt. When the scraper is centrally located the king-bolt passes down through the bolster, the center piece of 20 the hounds, the axle, and then through the yoke *v*, all as seen in Fig. 3; but the scraper is capable of being changed in position end-wise of the axle, and held in that position by the king-bolt, as will now be explained.

25 Two metallic plates, *z*, (partially seen in Fig. 1,) are secured to the axle *A*, one on its upper and the other on its lower side, and in this instance a short distance to the right of the center of the axle. These plates are provided with suitable holes for receiving the king-bolt.

When it is desired to change the position of the scraper the king-bolt is removed and the bolt removed from the foot *K*. The bolster is 35 then shifted to the right until its hole for receiving the king-bolt is over the holes in plates *z z*. The king-bolt is then dropped in place, and the foot *K* is again bolted in proper position on the tongue, while at the same time the 40 plate *T* may be suitably changed on the semicircle *I*.

g represents a cutter secured to or forming a part of the knife at one end. This cutter extends slightly upward and outward from 45 the knife, and may be made to cut a path for the wheel, while its obliquity draws in the earth from beneath the wheel to the scraper.

When the scraper is intended to run directly under the axle or square across the machine, 50 the king-bolt will pass down through the center of the axle; but when it is desired to have it move obliquely, or one end forward of the other, the king-bolt is shifted over to pass through the plates *z z*.

55 *C* represents a foot-piece for the driver of

the machine, and is bolted upon the semicircle and in front of the driver's seat, as seen.

The end of the tongue is provided, as seen in Fig. 5, with a metallic rod, which serves as a keeper for the neck-yoke ring. This rod is 60 bolted upon the top and to the bottom side of the pole, and a sufficient space is left between it and the end of the pole for the neck-yoke ring to pass around the end and work with above or below it, as may be required.

Having thus fully described my invention, what I claim as new, and desire to secure by Letters Patent, is—

1. The bolster *E*, capable of being detached and adjusted to different positions upon the 70 frame of the machine, and carrying with it the means for connecting it to and operating the scrapers, consisting of the levers *F*, chains *a* *a*, and pulleys *J J*, the several portions being constructed and arranged substantially as set 75 forth.

2. The semicircular brace *I*, connected to the rear of the scraper, in combination with the tongue having a rear adjustment at *x* and a forward adjustment by means of the brace *H*, 80 substantially as set forth, and for the purpose specified.

3. The scraper composed of the back board, *P*, the bed-plate *q*, and the cutter *R*, braced from the rear by means of the braces *u* and *u'* 85 and semicircular brace *I*, substantially as and for the purpose set forth.

4. The tongue *G*, provided at its rear end with the straps *S* and *T*, in combination with the scraper, the yoke *v*, the brace *u'*, and the 90 semicircular brace *I*, arranged in rear of the axle, substantially as and for the purpose set forth.

5. The combination of the scraper with the plates *z z* on the axle, the tongue *G*, as constructed, and with its brace *H* and the bolster *E*, with king-bolt *Y*, for the purpose of shifting the position of the scraper, substantially as specified.

6. The braces *u* and *u'*, hinged to the scraper 100 at one end and bolted to the tongue-plates near their rear end, substantially as and for the purpose specified.

In testimony whereof I affix my signature in presence of two witnesses.

JONATHAN FLEMING.
